UNITED STATES PATENT OFFICE

92,364

DESIGN FOR A BOTTLE

Albert C. Noble, Washington, Pa., assignor to Tygart Valley Glass Company, Washington, Pa.,
a corporation of West Virginia

Application April 7, 1934, Serial No. 51,348

Term of patent 7 years

To whom it may concern:

Be it known that I, OLBERT C. NOBLE, a citizen of the United States, residing at Washington, in the county of Washington, State of Pennsylvania, have invented a new, original, and ornamental Design for a Bottle, of which the following is a specification, reference being had to the accompanying drawing forming a part hereof.

Figure 1 is a face view of a bottle embodying my design; Fig. 2 is a side view thereof, and Fig. 3 is a plan view of the bottle.

I claim:

The ornamental design for a bottle, as shown.

OLBERT C. NOBLE.
